UNITED STATES PATENT OFFICE.

WALTER DE LATIMER, OF HOUSTON, TEXAS, ASSIGNOR OF ONE-HALF TO
W. H. BAILEY, OF HOUSTON, TEXAS.

HYDROCARBON-BURNER.

SPECIFICATION forming part of Letters Patent No. 728,683, dated May 19, 1903.

Application filed May 17, 1902. Serial No. 107,831. (No model.)

To all whom it may concern:

Be it known that I, WALTER DE LATIMER, a citizen of the United States, residing at Houston, in the county of Harris and State 5 of Texas, have invented a new and useful Hydrocarbon-Burner, of which the following is a specification.

This invention relates to hydrocarbon-burners; and it has for its special object to 10 provide a burner of this class which shall be especially adapted for the consumption of crude oil, which as a fuel is readily available at a very low price.

A further object is to construct a burner 15 which shall be exceedingly simple and inexpensive and any part of which when burned out or destroyed may be readily replaced at a nominal expense.

A further object is to provide a feeding device 20 for supplying the oil to the burner by means of which the oil shall be thoroughly agitated and aerated before being introduced into the burner, thereby increasing its heating capacity and facilitating its conversion 25 into gaseous vapor.

With these and other ends in view the invention consists in the improved construction and combination of parts, which will be hereinafter fully set forth, and pointed out 30 in the claims.

In the drawings hereto annexed, Figure 1 is a perspective view showing the hydrocarbon-burner constructed in accordance with my invention, the same being arranged for operation 35 in an ordinary cook-stove, which latter is shown in section. Fig. 2 is a diagrammatic view illustrating the feeding device and the pipes leading to the burner.

Corresponding parts in both figures are indicated by like characters of reference.

Connected with the inlet-valve 1 of a supply-pipe 2 is a horizontal pipe 3, from the outer end of which depends a short pipe-section 4, the lower end of which is connected 45 with the first generator-pipe 5, which latter is downwardly inclined, as shown. The outer end of the pipe 5 is connected by a short horizontal pipe-section 6 with the second generator-pipe 7, which is likewise downwardly 50 inclined, but in a direction opposite to that of the pipe 5. The inner lower end of the

generator-pipe 7 is connected by a vertical pipe-section 8 with the first burner-pipe 9, which is extended outwardly in the same vertical plane as the pipe 7. A short horizontal 55 pipe-section 10 connects the outer end of the pipe 9 with a similar pipe 11, likewise horizontally arranged and extending nearly to the pipe-section 4 of the inlet, where it is provided with a cap or closure 12. The several pipe-sections forming the burner are mutually connected by elbows 13 of ordinary construction. The burner-pipes are provided in their under sides with openings or apertures 14 for the burners, whereby the flames are deflected 60 upon the generator-pipes underneath.

It will be observed that while the burner-pipes 9 and 11 are arranged parallel to each other in the same horizontal plane the generator-pipes 7 and 5, which are located relatively 65 below the said burner-pipes, are inclined in opposite directions, the former being extended downwardly from the lower end of the latter. The latter pipe 5 being connected directly with the inlet, it follows that the oil 70 on entering said pipe is exposed to a greater degree of heat than in the pipe 7, which it enters in a partly-vaporized state. Possible danger from explosion by the superheating 75 of the vapor is thereby averted.

15 designates a tank, preferably constructed of cast-iron, which is located below the burner. One end of this, which constitutes the igniting-tank, is provided with an opening 16, through which extends a short downwardly-curved supply-pipe 17, the outer end of which almost reaches the bottom of said tank, as clearly shown in Fig. 1 of the drawings. The pipe 17 has a valve 18 suitably 80 connected with the supply-pipe 2.

The means for supplying the fuel-oil to my improved burner have been illustrated in the diagram of Fig. 2, from which it will be seen that the lower end of the supply-pipe 2 is suitably connected by a pipe 19 with a tank 20 of 85 suitable capacity, which may be buried in the ground outside the building in which the burner is used. The tank 20 has a valved filling-pipe 21, and the lower part of said tank has an air-inlet pipe 22, connected by piping 100 23 and a flexible pipe-section 24 with an air-current 25, adapted to be operated by a hand-

lever 26. By this means I am enabled not merely to produce the requisite air-pressure in the tank 20 for forcing the oil contained in the latter up into the burner, but the air 5 introduced through the pipe 22 is caused to churn and thoroughly agitate the oil, becoming commingled therewith and facilitating its conversion into a gaseous vapor which is better fitted for consumption than when unmixed 10 with atmospheric air.

The filling-pipe 21 of the tank 20 is provided at its upper end with an elbow 27, to which by means of a swiveled or union joint 27^a is connected a filling cup or funnel 28. The latter when not in use for filling the tank may be turned down to the reversed position shown in dotted lines in Fig. 2, when it will be seen that it forms a protection for the inlet of the filling-pipe, water, dirt, &c., being absolutely 20 prevented from entering the same.

In addition to the filling-pipe 21 the storage-tank is provided with a small pipe 29, having a petcock 30, by opening which the air contained in the tank may be permitted 25 to escape when the tank is being filled. By opening either this petcock or the valve of the filling-pipe the compressed air may at any time be permitted to escape from the storage-tank when it shall be desired to withdraw the 30 oil-supply from the stove—for instance, in case of fire.

The pipe 23, connecting the storage-tank with the air-pump, is provided with a check-valve 31 to prevent the oil from backing up. 35 This is very essential, owing to the arrangement of the mouth of said air-pipe below the level of the oil in the storage-tank.

The operation of my invention will be readily understood. By operating the air-pump 40 until a suitable pressure has been produced in the storage-tank the oil is caused to flow into the supply-pipe. By opening the valve 18 a small quantity of oil is permitted to flow into the igniting-tank 15. Being ignited, it 45 heats the generator-pipes until the oil, permitted to pass into the latter by opening the valve 1 of the supply-pipe, is converted into gaseous vapor, which on entering the burner-pipes and escaping through the burners is

ignited. The flames deflected by the burners 50 upon the generator-pipes will heat the latter sufficiently to cause the conversion of oil into vapor to proceed uninterruptedly as long as the valve 1 remains open and sufficient air-pressure exists in the storage-tank. 55

Having thus described my invention, I claim and desire to secure by Letters Patent of the United States—

1. A hydrocarbon-burner comprising a generator-pipe connected with and extending 60 downwardly and forwardly from the supply-pipe, a short connecting-pipe, horizontally disposed and extending laterally from the outer lower end of said generator-pipe, a second generator-pipe extending downwardly 65 and rearwardly from the said connecting-pipe, a vertical connecting-pipe extending upwardly from the inner lower end of the second generator-pipe and a pair of parallel, horizontally-disposed burner-pipes connected 70 at their outer ends by a short connecting-pipe, one of said burner-pipes being connected at its inner end with the upper end of the vertical connecting-pipe and the other burner-pipe being closed at its inner end, said 75 burner-pipes being disposed in the same vertical planes as the generator-pipes, said generator-pipes being tilted from their connected ends, respectively in an upward and a downward direction, being thus disposed at unequal distances from the respective burner-pipes and the latter being provided with flame-openings in their under sides, through which 80 flames will be projected in the direction of the generator-pipes. 85

2. The combination with a storage-tank buried under ground and having a valved inlet-pipe provided with an elbow at its upper end, of a filling cup or funnel swiveled to said elbow to exclude dirt when turned in a downward direction. 90

In testimony that I claim the foregoing as my own I have hereto affixed my signature in the presence of two witnesses.

WALTER DE LATIMER.
